FLUID PRESSURE SYSTEM

Romeo M. Nardone, Westwood, N. J., assignor to
Bendix Aviation Corporation, South Bend, Ind.,
a corporation of Delaware

Application December 26, 1940, Serial No. 371,845

2 Claims. (Cl. 277—55)

This invention relates to fluid pressure systems and particularly to the control of the direction of fluid flow therein.

An object of the invention is to provide a unitary mechanism by which fluid under pressure may be directed to any selected one of a plurality of fluid receiving units, but only so long as the pressure of the fluid remains within a predetermined pressure range.

Another object of the invention is to provide, in a unitary flow directing mechanism of the foregoing character, novel means for automatically diverting the flow to a different outlet when the pressure goes beyond the predetermined pressure range.

Another object of the invention is to provide, in a unitary mechanism of the foregoing character, novel means for varying the pressure range and thereby selecting the point at which the fluid will be diverted to a different outlet.

These and other objects and features of the invention are pointed out in the following description in terms of the embodiment thereof which is shown in the accompanying drawing. It is to be understood, however, that the drawing is for the purpose of illustration only, and is not designed as a definition of the limits of the invention, reference being had to the appended claims for this purpose.

In the drawing:

Fig. 1 is a top plan or end view of a device embodying the invention;

Fig. 2 is an exploded view of the rotatable parts;

Fig. 3 is a longitudinal sectional view;

Fig. 4 is a transverse view along the line 4—4 of Fig. 3;

Figs. 5 and 6 are transverse views of the intermeshing tongues of Fig. 2; and

Fig. 7 is a bottom plan view.

The flow controlling means is shown as being provided with an inlet port 1 adapted to direct the entering fluid into a chamber provided centrally of the mechanism and from which chamber the fluid may be directed into lateral openings in a rotatable hollow spindle 3, at the upper portion of which is another lateral port 3a (Fig. 4) from which the fluid may emerge into any selected one of the outlet ports 4 leading to various fluid receiving units, not shown; the selection of the particular outlet being determined by the rotation of the handle 5 pinned to the upper end of the spindle 3 and having a projecting index element adapted to register with any selected one of the reference characters located in a circle 55

along the upper surface of the valve mechanism as indicated in Fig. 1, the location of the reference characters corresponding to the angular spacing of the outlets 4. A spring-pressed ball 13 is adapted to cooperate with depressions 14 in the under surface of the hub 15 of the handle 5 and thus yieldably retain the handle in the selected position.

The hollow spindle 3 terminates in a series of unevenly spaced tongues or teeth 16, adapted to mesh with corresponding tongues or teeth 17 projecting upwardly from a disk 6 having apertures 7 therein, the spacing of said apertures 7 being uniform and corresponding to the spacing of the outlets 4. As shown in Fig. 3, the disk 6 is rotatable upon the flat upper surface of a transversely extending partition 18 shown as integral with the lower section 19 of the valve housing. In said lower section 19 there are two reciprocable valves 8 and 11 of the poppet type, each provided with a spring adapted to yieldably urge its valve into engagement with one of a pair of tapered seats 23 at the bases of a corresponding pair of apertures 21 located in the transverse partition 18; the angular spacing of these openings 21 of the partition 18 being indicated in Fig. 7 by the spacing of the nuts 8a and 11a—in other words, 135 degrees apart.

A screw mechanism 9, including the internally threaded cap-nut 8a, provides a means of adjustment of the pressure upon the spring of the valve 8 and thereby affords a means for regulating the pressure at which the valve will open. A similar mechanism may be provided with the cap-nut 11a of the valve 11, if desired, but it will be apparent as the explanation of the mechanism progresses that the system may function satisfactorily with one valve pre-set and the other adjustable at will to accommodate the operation to varying conditions.

With the foregoing construction in mind, it will be apparent that fluid entering at 1 passes through holes 2 in spindle 3 and out through one of the four outlets 4.

When handle 5 is turned clockwise to any one of the four positions, plate valve 6 is carried around with 3 so that one of four equally spaced holes 7 is in registry with the relief valve 8. If the pressure exceeds the valve setting, valve 8 opens and fluid goes out through outlet 10.

When the handle is turned anti-clockwise, the first 45 degrees of movement of spindle 3 is not transmitted as motion to valve plate 6, due to the provision of a 45 degree gap in the mating tongues or teeth, as indicated in Figs. 2, 5 and 6.

The second 45 degrees of movement carries plate 6 around so that one of holes 7 is in registry with the second relief valve 11, located 135 degrees away from 8. Thus only one valve is exposed to fluid pressure, while the other is closed. If the second valve is set at a higher value than the first, it will open only after the pressure has increased correspondingly. Thus there is provided a means for getting fluid at different pressures, at the outlet 10, depending upon the direction of turning the handle 5.

What is claimed is:

1. In a valve mechanism, a pair of excess pressure relief valves normally closed by spring pressure of different values, a ported plate controlling application of pressure to said valves, a third valve registerable with any selected one of a plurality of outlet ports, said third valve also having constant communication with said ported plate, and a single means for simultaneously shifting said third valve and said ported plate, the excess pressure relief valves being so spaced with respect to the ports in the plate and coordinated with said shifting means that on shifting the shifting means in one direction one of the ports in the plate will register with one of the excess pressure relief valves whenever the third valve registers with one of the selected outlet ports and when the shifting means is shifted in the opposite direction one of the ports in the plate will

register with the other excess pressure relief valve whenever the third valve registers with one of the selected outlet ports.

2. In a valve mechanism, a pair of excess pressure relief valves normally closed by spring pressure of different values, a ported plate controlling application of pressure to said valves, a third valve registerable with any selected one of a plurality of outlet ports, said third valve also having constant communication with said ported plate, and a single means for simultaneously shifting said third valve and said ported plate, the excess pressure relief valves being so spaced with respect to the ports in the plate and coordinated with said shifting means that on shifting the shifting means in one direction one of the ports in the plate will register with one of the excess pressure relief valves whenever the third valve registers with one of the selected outlet ports and when the shifting means is shifted in the opposite direction one of the ports in the plate will register with the other excess pressure relief valve whenever the third valve registers with one of the selected outlet ports, said single means including a driving member which produces different degrees of movement of said ported plate, according to the direction of movement of said driving member, and in response to equal degrees of movement of said driving member.

ROMEON M. NARDONE.
